CLAIM

I claim the ornamental design for a sprocket nose, as shown and described.

DESCRIPTION

FIG. 1 is a perspective view of a sprocket nose showing my new design in a position of use on a chainsaw guide bar;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the sprocket nose; and,

FIG. 9 is another perspective view of the sprocket nose.

The dashed lines are included for illustrating environmental structure and form no part of the claimed design.
